COMBINATION REMOVABLE SADIRON BASE PLATE AND HOLDER

Nathan K. Morris, 41 Ridge Ave.,
Neptune, N.J. 07753

Filed June 3, 1966, Ser. No. 2,555

Term of patent 3½ years

(Cl. D49—6)

FIG. 1

FIG. 2

FIG. 3

FIGURE 1 is a side elevational view of a combination removable sadiron base plate and holder embodying my new design;

FIGURE 2 is a bottom plan view thereof; and,

FIGURE 3 is a rear end elevational view thereof, with the holder omitted for convenience of illustration.

The side not shown has substantially the same appearance as the side shown.

The dominant features of my design reside in the portions shown in full lines, the broken line showing the sadiron being for illustrative purposes only.

I claim:

The ornamental design for a combination removable sadiron base plate and holder, as shown and described.
